JOE HAVASSY, OF MIAMI, ARIZONA.

INK WELL AND STAND.

1,100,874.

Specification of Letters Patent. Patented June 23, 1914.

Application filed August 14, 1913. Serial No. 734,738.

To all whom it may concern:

Be it known that I, Joe HAVASSY, a subject of the King of Hungary, residing at Miami, in the county of Gila, and State of Arizona, have invented certain new and useful Improvements in Ink Wells and Stands; and I do declare the following to be a full, clear, and exact description of the invention, such as will enable others skilled in the art 10 to which it appertains to make and use the same.

This invention relates to stationery, and more especially to fountain ink stands having a compressible bag; and the object of 15 the same is to produce a device of this kind in which the ink is forced from the well upward into the hopper by a pressure device set by hand, and in which the base of the framework or stand constitutes a pen wiper 20 and pen rack. This object is accomplished by constructing the device in the manner hereinafter more fully described and claimed, and as shown in the drawings wherein—

25 Figure 1 is a front elevation of this device. Fig. 2 is a central vertical longitudinal section. Fig. 3 is a cross section on the line 3—3 of Fig. 2. Fig. 4 is a perspective detail of the lever. Fig. 5 is a perspective 30 detail of the bracket.

The stand portion of this device comprises a box-like base 1 mounted on legs 2 and having a slightly raised preferably circular socket 3 at its rear end in which is removably mounted the casing 4 which may be of glass, metal, or any suitable material but is shown herein as cylindrical and having a top 5 with a large opening therein. In the box-like portion forward of the socket 3 is 35 disposed the pen-wiper which consists of a multiplicity of pieces or strips 6 of paper standing on edge and in close contact with each other, and on the upper edges of these strips the pen can be wiped or into and between them the pen can be inserted so that it stands upright as seen at P. It is quite possible that the entire framework of the base may be of metal, suitably ornamented to give it a fanciful appearance.

40 The ink holder comprises a well 10 here shown as consisting of a substantially hemispherical-shaped hollow member composed of flexible material such as elastic rubber and a hopper 11 preferably made of hard rubber and having a centrally disposed tapered or substantially cone-shaped mouth

piece 11'. The hopper member 11 is circular in shape when viewed from the top and on its outer wall is formed an integral outwardly projecting annular flange 13 adapted to rest on the top 5 when the ink holder is inserted in the casing 4, as will be readily understood on reference to Figs. 2 and 3. The rubber well 10 has its upper edge surrounded by a soft wire ring 12 which causes 45 the open top of the well to snugly fit the cylindrical wall of the hopper beneath the flange 13. Any suitable cover may be provided for the top of the hopper, but as shown, the cover 14 is dome-shaped and is 50 hinged at 14' and held closed by a catch 14", as will be understood on reference to Fig. 2.

The compression mechanism comprises a circular plate 20, the upper side of which is dished or concaved to receive and support the body of the hemispherical-shaped well 10. Formed on the bottom of the plate 20 are spaced apertured ears 21 which receive a pivot pin 21', the latter also passing through a reduced end or lug 23 formed on 55 the upturned lower end of a substantially J-shaped lever 22, shown more clearly in Fig. 4. The upper end of the lever 22 is reduced to form an apertured ear 24 which is pivoted on a pin 24' passing through spaced lugs 25' projecting at right angles from the upper end of a plate 25 rigidly fastened on the inner wall of the casing 4, see Fig. 3. In the lower portion of the plate 25 is a threaded opening to receive an adjusting screw 28 60 having a head or finger piece at its outer end. Its inner end is rounded to engage a wear plate 27 attached to a projection or enlargement 22", the wear plate being provided when the lever is made of wood or the like. 65 The projection 22" has its outer face opposed to the screw disposed in a substantially vertical plane, so that when the screw is turned in an inward direction the lever will be swung on its pivot 24' and its inner 70 end caused to swing the lever to raise the dished plate 20 so that the ink well 10 is compressed from its lower end whereby the ink is forced upward through the hopper 11 and rises to a sufficient height therein to 75 permit the pen to be dipped into it. When the device is out of use temporarily the cover is closed; when the device is to be out of use permanently, perhaps overnight, the screw 28 is given a few revolutions to the left and 80 the expansive tendency of the rubber of which the well is made will cause it to re-

85 90 95 100 105 110

sume its normal shape so that the ink within the hopper 11 will be sucked down out the same as will be clear.

To clean the device, the well with its hopper 11 is lifted out of the casing 4 and then the hopper is removed from the well so that both parts may be thoroughly cleaned. These parts are then put together and re-inserted in the opening in the top of the casing. Attention is directed to the fact that, although the base is rather heavy and there is little likelihood that this stand will upset, in case that accident should happen, the ink will be trapped within the well at one side of the hopper 11 and little if any of it will pass out into the mouth 11' even though the well be completely inverted. Otherwise than as herein stated, the materials of parts are not essential, nor their size and proportion.

What is claimed as new is:

The herein described ink well comprising an upright casing having an opening in its top, a bracket secured on the inner wall of the casing and having a threaded opening and spaced apertured lugs at its top, an ink

holder comprising an elastic hemispherical bag and a hopper removably arranged in its open top and formed with an annular flange to rest on said casing when the bag is inserted in the opening in the top of the casing, a J-shaped lever having at its top an apertured ear arranged between said lugs and a substantially vertical contact face disposed opposite said threaded opening in the bracket, the lower curved end of the lever extending inwardly and upwardly, a dished plate pivoted on said inner end of the lever and in contact with the bottom of said bag, a pivot passing through said lugs and ear, 40 and an adjusting screw passing through the casing and the threaded opening in the bracket for engagement with said vertical face of the lever, substantially as shown and described.

In testimony whereof I have hereunto set my hand in presence of two subscribing witnesses.

JOE HAVASSY.
